UNITED STATES PATENT OFFICE.

WARREN COLLINS AND CHARLES F. PENNIMAN, OF JANEVILLE, WIS.

HARNESS-BUCKLE.

SPECIFICATION forming part of Letters Patent No. 228,872, dated June 15, 1880.

Application filed December 15, 1879.

To all whom it may concern:

Be it known that we, WARREN COLLINS and CHARLES F. PENNIMAN, of Janesville, in the county of Rock and State of Wisconsin, have invented a new and useful Improvement 5 in Harness Buckles, which improvement is fully set forth in the following specification and accompanying drawing.

Our invention relates to buckles, and the 10 object of it is to hold a trace or strap firmly by the use of a metallic plate to take the place of the ordinary buckle-frame, and which may be solid or open and ornamented upon its outer surface, and a rigid tongue in connection with 15 a clamp or curved loop to relieve the strain at the hole provided for the tongue and to hide the same from view.

The drawing is a plan view of the outer surface of the metallic plate and an inner perspective view, showing clamp and tongue.

Our invention consists of a metallic plate, A, slightly convex on the outer surface, which is ornamented with such designs and figures as may please the fancy, on the inner surface 25 of which are provided fastenings to hold the straps of a harness, this plate to be of such convenient size as may be found necessary, according to the place where it is to be used. For a trace-buckle, upon the inner surface of 30 said plate A is located, near the rear end, a rigid tongue, a, projecting inwardly and slightly inclined forward to enter a perforation provided for it in the trace, in connection with a clamp, B, forming a loop, d, at the forward end to receive 35 the hame-tug, said clamp being on a curve inwardly and sliding within the cross-bar b, its side bars running in notches E E provided for them at each side of plate A, said plate having two spurs, f f, projecting inwardly 40 at the rear end and on each side, to operate as

guards to the trace. The clamp is provided with a flat rear end bar, g, resting on the trace at the rear end just forward of the rigid tongue, the side bars of the clamp being slightly curved inward, the convex side of said clamp running 45 on the inner surface of plate A on each side of the trace, the flat cross-bar g bearing upon the trace, the under side being corrugated to hold the same from slipping, and when strain is applied the clamp operates as a wedge and 50 hugs the trace to the plate. The clamp passes freely under bar b, and is easily released when the strain is withdrawn; and the forward inclination of rigid tongue a holds the trace firm when in place, but at the same time permits it to be easily released and adjusted by 55 simply crowding it forward, when it will slip off the tongue.

We make no kink or bend in the trace, but simply bind it to a flat surface by means of 60 clamp B.

We do not confine ourselves to any form of attachments to the inside of plate A, but devices for buckles are applied to it, and whether the plate is made solid or open, as shown, the 65 inside fastenings may be variously arranged.

What we claim as our invention, and desire to secure by Letters Patent, is—

The metallic plate A, as hereinbefore set forth, provided with rigid inclined tongue a, 70 cross-bar b, having notches e e, and guides f f, in combination with curved clamp B, all arranged and used substantially as described, and for the purposes mentioned.

WARREN COLLINS.
CHARLES F. PENNIMAN.
